UNITED STATES PATENT OFFICE.

EMIL GATHMANN, OF BETHLEHEM, PENNSYLVANIA.

PROJECTILE.

No. 904,255.

Specification of Letters Patent.

Patented Nov. 17, 1908.

Application filed December 7, 1907. Serial No. 405,488.

To all whom it may concern:

Be it known that I, EMIL GATHMANN, a citizen of the United States, residing at Bethlehem, Northampton county, Pennsylvania, have invented certain new and useful Improvements in Projectiles, of which the following is a specification.

The objects of this invention are to produce an armor piercing projectile containing for a given size or weight and mass of head a minimum of initial strains, bordering on rupture.

Other objects are to provide a construction which allows of uniform and efficient hardening and tempering of the large, as well as the small and medium sizes of armor piercing projectiles.

Further objects are to improve the details of construction of such projectiles.

My invention relates to that type of projectiles termed armor piercing shot and shell by those familiar with the art. The head or forward portion of these projectiles are usually made very massive, and the body or rear portion contains a cavity or explosive charge chamber. It is extremely desirable that the head or forward portion of the projectile be so hardened and tempered as to enable the projectile when impacting with a suitable velocity to penetrate the extremely hard and tough armor plates produced by the Krupp and other systems. At the present date, specifications relating to armor piercing projectiles, prescribe a test in which the projectile must perforate a hard faced armor plate equal to the Krupp standard of a thickness of at least one caliber or diameter of the projectile, with the requirements that there be no breaking or cracking of any portion of the latter so as to expose the charge cavity.

Although the armor piercing projectiles are at the present time being made of high grades of alloy steels and are hardened and tempered with skill and care, a great many projectiles fail to pass the prescribed ballistic tests. The most frequently occurring manner of failures that I have personally witnessed during the past seven years were due to the shattering of the head of shell and consequent exposure or opening up of the forward end of the charge cavity. This danger of shattering or rupturing of the head of the projectile upon impact with modern armor plate becomes relatively greater, the larger the size or diameter of

the projectile and the more massive the forward end or head.

From the many ballistic tests of projectiles that I have witnessed and from a number of experiments made, I have determined that the shattering and rupturing of the usual constructions of armor piercing projectile heads, is due mainly to excessive initial strains in the mass of the metal composing the head, which strains are caused by the rapid necessary cooling of the hardening processes, and the consequent shrinkage or contraction of the large mass of the outer portion of the metal upon the practically unyielding inner axial core or central mass of metal, which being thus subjected to a compression beyond its normal shrinkage dimensions, exerts an initial outward pressure bordering on rupture.

I have seen a great number of armor piercing projectiles, the points and heads of which have ruptured spontaneously within a short period of elapsed time after hardening treatment. In my improved projectile, I so construct the head portion that the internal rupturing strains due to hardening treatment as previously described, will be much reduced or practically eliminated. I also provide a construction of the point of the head of the projectile whereby should the point be shattered or cracked, during penetration of an armor plate, the cracks or shattering action will not be readily transmitted to the major portion of the head, the danger of exposure, or opening up of the charge cavity being thus greatly reduced.

In order to obtain a good bursting effect of the projectile due to the explosion of the cavity charge of explosive material, it is essential that the cavity be strongly inclosed and that no openings exist through which the gases would readily issue without properly fragmenting the shell.

Several forms of the invention are illustrated in the accompanying drawings, in which—

Figure 1 is a longitudinal central section of a projectile embodying the invention. Fig. 2 is a longitudinal central section of another shell embodying the invention.

Similar letters represent like parts throughout the drawings.

The practically cylindrical body A of the projectile contains a charge chamber B provided at its rear end with a threaded portion C adapted to engage with a suitable

base plug D. The relatively massive head E is provided with a centrally located longitudinal bore F, said bore extending from the forward end G of the head E closely to, 5 or into the charge chamber B, barrier block H being provided to separate the charge chamber B from the bore F, said barrier block H being integral with the projectile when the bore F does not extend or open 10 into the chamber B, as shown in Fig. 1.

When the bore F extends into the charge chamber B as shown in Fig. 2, the barrier H is suitably secured at or near the forward end of the charge chamber B. The barrier 15 may be built up as shown by bushing M and plug N, and the said plug N may be adapted to carry a shell fuse O if so desired.

In assembling the projectile a point I is secured to the forward end G of the head, 20 a washer K, being preferably inserted between the said point and head. A cap L of any desired form is then preferably placed over the said point I, the cap being locked to either the point I or the head E of the 25 projectile in any of the usual ways. The cap L may however be omitted in certain type of projectile in which case I prefer to use a thicker washer K as shown in Fig. 2. I prefer to center and fasten the point I to 30 the head E by means of a shank P which extends from the said point I and is adapted to enter into the bore F a suitable distance to insure of proper guiding and support. The contact surface of the rear part 35 of the point I and the forward part G of the head E is preferably slightly cone shaped, the washer K being formed to fit said coned or tapered surface. The point I is preferably fitted to the head E of the 40 projectile after the latter has been hardened and tempered, the point I being itself hardened and tempered before assembling to the head of the projectile.

In hardening the head E of my construction of projectile, the mass of metal will contract inwardly in the usual manner due to rapid cooling of the same; the bore F will however allow of an inward movement or flow of the metal as the natural decrease in 50 the volume of the head takes place, thus initial strains such as obtain in a solid headed projectile will not occur, as the bore F provides for an inward flow of metal, which flow in the solid headed projectile is impossible as the pressure on the interior solid 55 portion caused by contraction of the outer portion results in a reactionary pressure tending to disrupt the said outer portion. It is evident, the larger the projectile the more 60 pronounced is this action, as the cooling is necessarily slower with increased diameters, the surface increasing in direct ratio to the diameter, while the volume of metal increases as the square of the diameter. I 65 therefore vary the diameter of the bore F to

suit the caliber of the projectile or the mass of metal in the head of the same, thus allowing for increased changes of volume. If, in the hardening treatment, cooling from the exterior only is desired, which method I prefer, the bore F is plugged with a suitable material such as fire clay, asbestos or the like so that the cooling medium will not act on the same directly. 70

It will be evident that my invention may 75 be embodied in many other forms than those illustrated, as obviously the shrinkage bore F may be advantageously employed in projectiles having different shaped heads and points than those shown in the drawing and 80 specifically described:—For instance; a projectile could be employed without the point I and washer K being fitted to the head E, and if desired the point could be made integral with the head of the projectile. 85

Therefore, without limiting myself to the precise construction illustrated and described, I claim:—

1. An armor piercing projectile provided with a point a charge chamber an axial bore 90 forward of said charge chamber and a barrier separating the latter from the aforesaid bore, said barrier being integral with the major mass of the projectile, but not with the point of the same. 95

2. An armor piercing projectile provided with a point a charge chamber in its rear and a shrinkage bore in its head portion and a barrier separating the latter from the charge chamber, the said barrier being secured to the major mass of the projectile, but not to the point of the same. 100

3. An armor piercing projectile provided with a point a bursting charge chamber in its rear and an axial shrinkage bore in its 105 head portion the said bore being closed at its rear end by a barrier and at its forward end by the projectile point, the said point not being integral with the major mass of the projectile, or with the separating barrier. 110

4. An armor piercing projectile provided with a shrinkage chamber in its head portion and a charge chamber in its rear or body portion, a separable point covering the forward opening of the shrinkage chamber 115 and the forward end of the head portion of the projectile, in combination with a washer having a conical bearing surface interposed between said head portion and the point of projectile. 120

5. An armor piercing projectile provided with an axial bore in its head portion and an explosive chamber in its body portion a barrier separating the latter from the bore, a separable point covering the forward end 125 of the said bore and the forward portion of the head of the projectile in combination with a washer interposed between the said forward portion of the head and the aforesaid point, the surfaces of contact of said 130

- projectile head, point and washer having a conical contour.
6. An armor piercing projectile provided with a charge chamber an axial bore forward of said charge chamber, and separated from the same by a barrier, a hard metal point covering said bore and centered on the projectile by means of a shank extending into said bore.
- 10 7. An armor piercing projectile provided with a charge chamber in its body portion and a shrinkage chamber in its head portion, a barrier separating said chambers located at the rear end of the said shrinkage chamber 15 a body of hard metal covering and extending into the forward portion of the said shrinkage chamber, said body being separated from and not in contact with the aforesaid barrier as and for the purpose specified.
- 20 8. An armor piercing projectile provided with a charge chamber a shrinkage chamber forward of said charge chamber, and separated from the same by a barrier, a body of hard metal covering and extending into the 25 forward portion of the shrinkage chamber said extension however not contacting with the aforesaid barrier, and a cap of relatively soft and tough material covering the said
- body of hard material as also a portion of the head of the projectile the cap being secured to the said head portion.
9. An armor piercing projectile provided with a charge chamber an axial bore forward of said charge chamber, and separated from the same by a barrier, a hard metal point covering said bore and centered on the projectile by means of a shank, and a cap of relatively soft and tough material covering the said hard metal point and also a portion of the head of the projectile and means for fastening the cap to said head.
10. An armor piercing projectile provided with a charge chamber an axial bore forward of said charge chamber, and separated from the same by a barrier, a hard metal point covering said bore and centered on the projectile by means of a shank, and a cap of relatively soft and tough material covering the said hard metal point and also a portion of the head of the projectile, in combination 45 with a washer interposed between the hard metal point and the said head of projectile.
